METHOD OF FORMING SHEET METAL

Howard M. Jager, Oceanside, N. Y., assignor to
Republic Aviation Corporation, a corporation
of Delaware

Original application November 3, 1942, Serial No.
464,357. Divided and this application June 30,
1943, Serial No. 492,795

4 Claims. (Cl. 153—48)

This invention relates to forming flat sheets of metal into various shapes by the employment of methods involving a drawing or stretching action and has more particular reference to a method involving provisions for anchoring or holding the work sheet during said drawing or stretching operation. This application is a division of application Serial Number 464,357, filed November 3, 1942, which matured into Patent Number 2,378,482 on June 19, 1945.

The general object of the invention is to provide a practical method of draw-forming or sketch-forming sheet metal into hollow aircraft components of curved shape such as metallic wing leading-edge sections and the like.

A particular object is to provide a sheet metal forming method, involving a stretching operation, in which the work-holding means will apply a holding-pressure that will be entirely independent of the stretching strain or load, so that there will be no possibility of the sheet being torn by the machine or becoming released during the stretching or forming operation.

A more specific object is to provide a sheet metal forming method, involving a drawing action, wherein the holding pressure, or grip, of the holding means on the work sheet can be accurately set to the desired amount before the machine is operated and yet can be readily adjusted for any desired load lying between the elastic limit and the ultimate tensile strength of the work sheet; but which will nonetheless apply a differential pressure on the held parts of the sheet and whereby the stretching or drawing load applied will be progressively absorbed and met by progressively increasing sheet-retaining forces.

A further particular object is to provide a method which will spread the holding grip over a much larger area of the work sheet than the subsistent work holding means; and in which all the acting surface of the work holding means, though of this improved nature, will be incapable of forming weakening punctures or indentations or other deformations in the held part of the work sheet, and will be perfectly smooth and obviate the employment of any kind of gripping teeth or projections.

In short this invention resides in the several successive steps or manipulations, hereinafter described in detail, for the conversion of a flat metal sheet into a hollow body, such as aircraft components, for example, the leading edge of a wing and proposes a method whereby the ultimate form of the body is attained by stretching a preformed sheet beyond its elastic limit while

opposed edges thereof are clampingly held against slippage or release by the application of progressive, multiple clamping pressures in an aggregate always exceeding the stretching force applied to the body of the sheet between the clampingly held edges.

While it is important to so preform and clampingly engage the opposed edges of the sheet that there will be no tearing of the sheet during the 10 final step of the instant method, it is equally important that the opposed edges be held against movement during the stretching operation and that only a minimum of the sheet be preformed for the purpose of creating clamping or engaging 15 zones.

Several embodiments of the inventive objects and concepts are described hereinafter and shown in the accompanying drawing, but it is to be understood that the invention is limited in its embodiments only by the scope of the subjoined 20 claims.

In the drawing

Figure 1 is a fragmentary end elevation of a sheet metal forming machine embodying a preferred form of apparatus for carrying out a part 25 of the instant method;

Figure 2 is a partial transverse section showing a modification of the clamping instrumentalities shown in Figure 1;

Figure 3 is a force diagram showing the action 30 of the forces in the clamp of Figure 2; and

Figure 4 is a fragmentary bottom plan view of the clamp of Figure 2, with certain parts in section.

The forming machine shown in Figure 1 is there applied to form a skin of a leading edge section of an airplane wing and includes a stationary 35 form block 11, carried on a platen 12 of a conventional hydraulic press and a saddle-shaped frame 13 to which the metal sheet is clamped and which frame is acted upon by the ram (not shown) of the hydraulic press.

The metal sheet 20 to be formed is bent beforehand to conform roughly with the shape of the 45 block 11 and has its opposite longitudinal edges bent twice in a "brake" so as to form two externally projecting U-channelled retaining borders. Thus prepared, the sheet 20 is slid endwise over the block 11, while each of said U-borders is inserted between two longitudinal beams 14 and 17 forming the upper and lower jaws of a clamp.

In the upper jaw 14 is provided a longitudinal dovetailed recess 15 in which works a longitudinal wedge-shaped gang nut 16, cooperating with 50 a series of screws 18 for gripping and anchoring

the U-shaped ends of the work sheet 20. One side 19 of the lower jaw 17 is slightly higher than the other to compensate for the thickness of the sheet 20.

When thus clamped in position over the form 11, the work sheet 20 can be stretched by lowering the ram of the press over the frame 13 until the sheet is deformed and assumes permanently the shape of the form. During this operation, there is no risk of tearing the work sheet along the inner bend of the U-borders, even if the pressure exerted by the ram rises beyond the ultimate tensile strength of this sheet, due to the fact that the gripping pressure is independent of the stretching force and is adjusted by tightening the screws 18 to the desired value lying between the elastic limit and the tensile strength of the sheet, and also due to the fact that the gripping pressure is spread over a relatively large area of the sheet, i. e., the wing of the U-border is pressed between the wedge 16 and one slanting side of the recess 15 and the bottom of the U-border is pressed between the two jaws 14, 17, thus providing a "differential" clamping action.

After the sheet 20 is thus formed—here, into a leading-edge skin section—the ram of the press is raised, the screws 18 are loosened and the section is removed endwise from the gripping jaws 14, 17.

Figures 2 and 4 show a slightly modified form of the preferred embodiment of the clamp. In this form, the ledge or thicker part, 19, is replaced by a shim 19' corresponding to the thickness of the work sheet 20 and the standard screws 18 are replaced by studs 33 provided with left and right-hand threaded portions. On the lower threaded portion of each of said studs is screwed a cylindrical nut 34 carrying two diametrically opposed trunnions 35 on which is swivelled the forked end 36 of a handle in two parts 37 fastened together by means of short bolts 38. The curved part of the fork 36 forms an eccentric or cam 39 allowing for a quick operation of the clamp after it has been adjusted by turning the studs 33 with a screw-driver.

The handles 37 may be locked in their active position by means of latches 40, pivoted as at 41 to a bracket 42 mounted on the side of the lower jaw 17'. Each latch 40 swings in a slot 43, formed between the two parts of each handle 37, when said handle meets a ramp 44 formed at the free end of the latch.

Figure 3 shows diagrammatically the relative magnitude and directions of the four reaction forces P_1 , P_2 , P_3 , and P_4 , which oppose the stretching force P when the clamp is closed and the machine operated. As in this specific embodiment angle $\alpha=100^\circ$ and angle $\beta=80^\circ$, and as the pressure applied by the wedge 16 or 16' on the upturned wing of the U-channel is substantially greater than the pressure applied by the jaw 17 or 17' under the bottom of the U-channel, the following conditions obtain:

- (1) $P_1+P_2+P_3+P_4 = P$; and
- (2) $P_1 < P_2 < P_3 < P_4$

By thus setting up four distinct clamping forces, and increasing their magnitudes; and by spreading these forces over a much larger area than in subsistent clamps, stress concentration at the point where the sheet leaves the clamp is avoided, thereby entirely obviating the tendency of the sheet to tear at this point. This tendency of the sheet to tear is further effectively precluded by having all the active surfaces of the jaws

of the clamps perfectly smooth, as distinguished from the clamps of the kind in which said surfaces are roughened, or provided with small teeth, in order to increase their gripping action.

It is to be understood that each of the opposite longitudinal edges of the work sheet is formed with angled borders, or compound bends—here disclosed as twice bent—merely in order to facilitate clamping and holding of the work sheet and in the ultimate product, these bends need not appear.

It is to be noted that although the triple-jaw clamp employed in carrying out the present invention, when operated by the tightening means disclosed, applies a differential pressure over different portions of the compound bends of the angled borders of the work sheet, it applies this pressure progressively, and over the entire, total surface of the pre-formed borders, with this pressure increasing most toward the extreme edges of the work sheet. Moreover, the stretching load is taken up, progressively, and in sequence, by four increasing, retaining-forces: by a first, rounded bend between the main portion of the work sheet and each of the angled borders; by the friction indirectly created between the fixed jaw and one of the movable jaws of the clamp; by a second rounded bend forming the angle of each border; and by a second frictional reaction created directly between the fixed jaw and the other movable jaws of the clamp.

The foregoing describes in detail the stretch press employed in carrying out the ultimate or final forming of the sheet 20 into a hollow body and also describes the novel clamping means co-operating with the preformed opposed edges of the sheet 20 all of which forms the subject matter of the mechanical or means parent application Serial No. 464,357 above referred to.

However, it is manifest that the structure shown and described is not essential per se to the practice of the present method, but is solely an example of the type of stretch press or apparatus especially suitable to the final forming of the sheets as taught by the present method. The present invention consists in preforming the opposed edges of a flat metal sheet 20 to create a U-channel at each edge thereof projecting from and above the same surface of the sheet. The creation of each of these channels is accomplished by bending a terminal flange 20'' from the edge of the sheet at an acute angle to the sheet so that the terminal flange 20'' extends over the body of the sheet. A base flange 20' is formed by bending the sheet adjacent the terminal flange 20'' to rest substantially at right angles to the body of the sheet whereby the terminal flange 20'' is positioned above the sheet to converge toward the sheet. These operations may be performed by any suitable means but it has been found that a "brake" is especially adaptable for that purpose. Upon the completion of the formation of the U-channels, the relatively flat sheet 20 has the base flange 20' projecting from each opposed edge thereof, said flanges being substantially parallel one to the other, and each, above the same surface of the sheet, is provided with a terminal flange 20'' converging inwardly toward the sheet. Thus the U-channels at this point in the method face and open toward one another.

The sheet 20 is then roughly or partially preformed by bending it medially between the U-channels at the edges of the sheet 20 to bring said channels into rather widely spaced positions upon

the exterior of the roughly preformed hollow body, the base flanges 20' then resting in substantially the same plane while the terminal flanges 20'' converge towards the outer surface of the roughly or partially preformed body.

The body thus roughly or partially preformed is then slid or otherwise placed upon the press form block 11 as above described and the U-channels at its edges are clamped as hereinbefore set forth.

It will be again noted that the clamping force P^2 is normal to the base flange 20' while the clamping force P^4 exerted on the terminal flange 20'' is normal to that flange. It will also be observed that there are 4 points of clamping or retaining pressure, viz.: P^1, P^2, P^3 and P^4 , and that the clamping pressure P^4 exceeds in value that of any of the other clamping or retaining pressures and that the clamping pressure P^2 exceeds the value of the clamping or retaining pressures P^1 and P^3 . The total of these pressures, P^1, P^2, P^3 and P^4 at all times exceeds the stretching force or pressure P exerted on the inner surface of the partially preformed sheet 20.

Manifestly, the formation of the clamping or engaging zones at the opposed edges of the sheet 20 is such that only a minimum of material is required and yet the formation thereof is such that there is no slippage or movement of these clamping or engaging zones during the stretching of the sheet 20 by internal pressure to its ultimate or final form. This not only is a saving in metal but insures complete dimensional accuracy in the finally formed hollow body which is vital to mass production and assembly.

Having thus disclosed the inventive concepts and several forms of embodiment thereof, what is claimed is:

1. The method of forming hollow bodies from flat metal sheets consisting in creating clamping zones at the edges of a flat sheet positioned substantially at right angles to the body of the sheet and projecting from and above the same surface of the sheet, roughly preforming the sheet by bending it medially between said clamping zones in a direction opposed thereto, clampingly engaging said zones by the application thereto of multiple clamping pressures progressively increasing in value toward the inner edge of each clamping zone, and finally forming the body by applying a stretching pressure to the face of the sheet opposed to said angularly disposed clamping zones of a value less than the aggregate clamping pressure applied to each clamping zone.

2. The method of forming hollow bodies from a flat metal sheet consisting in forming terminal flanges at the opposed edges of a sheet disposed at acute angles to the sheet and each extending inwardly over the body of the sheet, forming base flanges adjacent to each terminal flange by bending the sheet at right angles adjoining each terminal flange to position the terminal flange over the body of the sheet in a position at acute angles to both the sheet and the base flange thereby creating channels at the opposed edges of the sheet opening toward each other and projecting above the same surface of the sheet, roughly preforming the sheet by bending it me-

dially between said channels in a direction opposed to the channels to position the base flanges in substantially the same plane, clampingly engaging said channels externally of the roughly preformed body by applying thereto clamping pressures progressively decreasing in value from the terminal flanges to the inner extremities of the base flanges, and finally forming the sheet while the channels are clampingly engaged by applying pressure internally thereof in a direction substantially normal to the plane of the base flanges of the channels.

3. The method of forming hollow bodies from a flat metal sheet consisting in forming terminal flanges at the opposed edges of the sheet disposed at acute angles to the sheet and each extending over the body of the sheet, forming a base flange adjacent to each terminal flange by bending the sheet at right angles to position the terminal flange over the body of the sheet in a position at acute angles to both the sheet and the base flange thereby creating channels at the opposed edges of the sheet opening toward each other and projecting above the same surface of the sheet, roughly preforming the sheet by bending it medially between said channels in a direction opposed to the channels to position the base flanges in substantially the same plane, clampingly engaging said channels by applying clamping pressure to the base flanges and to the terminal flanges thereof, the clamping pressures applied to the terminal flanges being greater than those applied to the base flanges, and subjecting the roughly preformed sheet to an independent forming pressure on the face thereof opposed to the face carrying said channels, while said channels are clampingly engaged as aforesaid.

4. The method of forming hollow bodies from a flat metal sheet consisting in bending opposed edges of the sheet to form terminal flanges disposed at acute angles to the sheet and extending over the sheet, bending the sheet at right angles adjacent each terminal flange to form a base flange thereby positioning each terminal flange over the body of the sheet at an acute angle to both the sheet and its base flange and thus creating channels at the opposed edges of the sheet opening toward each other and projecting above the same surface of the sheet, roughly preforming the sheet by bending it medially between said channels in a direction opposed to the channels to position the base flanges in substantially the same plane, clampingly engaging said channels by applying independent clamping pressures to the base flanges and to the terminal flanges thereof, the clamping pressure applied to the terminal flanges being greater than those applied to the base flanges, and completing the formation of a hollow body by subjecting the roughly preformed sheet with its channels clampingly engaged to a final forming pressure internally thereof of less value than the aggregate values of the clamping pressures applied to the terminal flange and base flange of each channel, said forming pressure being from a source independent of the several clamping pressures aforesaid.

HOWARD M. JAGER.
